(57) **CLAIM**

The ornamental design for a boat hull pad, as shown and described.

DESCRIPTION

FIG. 1 is a perspective view of a boat hull pad, showing the front, bottom, and left side of our new design.

FIG. 2 is a front elevational view.

FIG. 3 is a top plan view, the bottom plan view being a mirror image thereof.

FIG. 4 is a left side elevational view, the right side elevational view being a mirror image thereof; and,

FIG. 5 is a rear elevational view.

The broken lines represent portions of the article that form no part of the claim. The broken away symbols in the drawings indicate the appearance of any portion of the article between the break lines forms no part of the claimed design.
